FIG. 2.

FIG. 4.

G. I. - 6
INVENTOR
Will Y. Cresser
by John W. Strehli
ATTORNEY.

UNITED STATES PATENT OFFICE.

WILL T. CRESSLER, OF CINCINNATI, OHIO.

HAND-STAMP.

1,398,363.

Specification of Letters Patent. Patented Nov. 29, 1921.

Application filed September 19, 1921. Serial No. 501,629.

To all whom it may concern:

Be it known that I, WILL T. CRESSLER, a citizen of the United States, residing at the city of Cincinnati, in the county of Hamilton and State of Ohio, have invented certain new and useful Improvements in Hand-Stamps, of which the following is a specification.

My invention belongs more particularly to that class of hand stamps, known as hand daters, which are generally employed in stamping dates upon letters, receipts, documents, bills and the like in connection with a permanent stamp, the dates being placed upon endless rubber belts or bands and the permanent stamp being upon a rubber pad, attached to a plate at bottom of the stamp; the dates usually consisting of day, month and year, symbols or characters, and being movable so that different dates can be used; the endless belts or rubber bands may carry any other figures, letters, symbols or the like, or any words.

My invention relates more particularly to the novel arrangement and combination of parts, rendering it possible for the user to adjust the rubber bands or belts properly so that the printing face of the bands will be in unison and flush with the face of the permanent rubber pad on the plate of the stamp, so that the matter on the pad and on the belts will all print even and at the same time, thus producing a uniform and legible print; and the feature and advantage consists in enabling me to accomplish this result without the use of any extraneous tools, such as screw drivers, knives or the like; the desired result can be obtained by manipulating the device itself. I accomplish this by producing a tension device placed at the bottom of the rubber bands, on the inside loop thereof, at said bottom part thereof, and manipulate the same by the handle of the stamp through agency of means connected with the shaft which carries the rolls over when the bands pass; thus enabling me to tighten or loosen the bands as needed, thus allowing one to always maintain the proper and needed tension.

In the accompanying drawing forming part of this specification:

Figure 1, is a side view in elevation of the device,

Fig. 2, is a sectional view, taken on the line 2—2 of Fig. 3,

Fig. 3, is a sectional view, taken on the line 3—3 of Fig. 2, and

Fig. 4, is a sectional view, taken on the line 4—4 of Fig. 2.

In carrying out my invention, in the present instance, I place on a shaft 20, a series of rolls or rollers 1, 2, and 3 upon which are mounted and over which pass the rubber belts or bands 4, 5, and 6; the rollers 1 and 3 being turned by serrated wheels 7 and 8 and the wheel 2 carries and is turned by two serrated wheels 11, one on each side of said roller 2, the bands at their lower turn pass over a tension bridge made up of the upper span 9 and the lower span 10; between these spans I provide pins as 12, and around pins 12, I place the coiled springs 13, pins 14 being also provided to guide the parts and keep them in alinement; the pins 12 passing through the lower span 10 enabling the spans to move toward or away from one another. The serrated wheels are rigidly connected to the rolls to which they are attached, so that when they turn the rolls, the bands or strips can be turned to move upwardly or downwardly to change the date, month, year or any other matter on the bands, so that different printing can be done by the dater, to suit the occasion or time.

In connection with the middle roll 2, I attach an arbor 15, which passes over the roll 2 and its wheels 11, arching the same, and the shaft 20 passes through the lower extremity of said arbor at the point 16. To the top part of arbor 15, at the point where it arches over wheel 2 and its serrated wheels, I rigidly connect to said arbor, at point 17, one end of a stem or rod 18, which rod at its upper extremity is screw threaded as shown at 19, a washer or centering plug 19¹ being present on the rod or stem 18, to always center the same, inasmuch as said rod being connected so that it will swing by reason of arbor 15 being loosely connected on shaft 20, said rod must be guided and centered.

All the working parts above described are housed in a framework in the present instance consisting of two complementary parts 21 and 22 and a plate 23, which when united by screw 23¹ at the bottom and handle 24 at the top, appear as shown in the drawing. When these parts 21 and 22 are assembled it will be seen that a slip collar 110

or stem 25 is formed at the top, upon which the handle 24 can be slipped on and off, and guideways as 26, are formed in which the ends of shaft 20 are supported, and shoulders as 27 are formed at the bottom so that the bridge formed of spans 9 and 10 can be placed to abut against said shoulders and the plate 23, (see particularly Figs. 2 and 3).

10 The serrated wheels 7, 8 and 11 pass through slits or slots in the side parts or pieces 21 and 22, (as shown in Fig. 1).

In the handle 24, I place an annular recess 30, which fits onto the slip collar 25. 15 In the handle 24, I place a depending screw threaded sleeve 31, which works on and off the screw threads 19 on the rod or stem 18.

In the plate 23, I place a permanent rubber printing pad 32, which always prints 20 the same matter in unison with the changeable matter printed by the endless belts 4, 5, and 6.

It will be noticed that the tension bridge spans 9 and 10 and connections are within 25 the looped bands 4, 5 and 6, at the bottom thereof, the lower band 10 being wedge shape to better connect the bands; it will also be noticed that the rolls 1, 2 and 3 and their wheels are mounted on the shaft 20 30 and that the arbor 15 is loosely connected to said shaft, and further that the stem 18 is rigidly connected to the arbor, and that the screw threaded sleeve 31 engages screw threads 19 on the rod or stem 18, consequently when the handle 24 which carries 35 the sleeve 21 is revolved to the right or left it screws down or up on said rod or stem 18 and thus lowers or raises the shaft 20 carrying all the rolls, wheels and the bands passing 40 thereover, downward or upward, operating the tension bridge so that its spans 9 and 10 will come closer together or farther away from each other to increase or diminish the tension on the bands or belts which 45 carry the rubber type thereon; by this operation taking up any play or tightening the same for any purpose whatsoever; keeping the face type on said bands flush with the permanent pad 32 in the plate 23. It 50 may be remarked here that the rubber pads 32 are not always the same thickness; this makes no difference with my device, as by turning the handle 24 in the proper direction, as heretofore stated, the bands can be 55 tightened or loosened to properly make the printing face in connection with the pad 32.

It will be seen from this description that I need no extraneous means for manipulating the parts to secure the proper alinement or tension on the movable parts of my 60 stamps.

While I have described one specific means and form for carrying my invention into effect, it will be readily apparent that the same may be used in connection with hand 65 stamps other than the one herein set forth, and that the same may be changed and modified without departing from the spirit or principle of my invention.

What I claim as new and my invention 70 and desire to secure by Letters Patent is:

1. In a device of the character described, a series of rolls and means for supporting the same, a series of endless rubber bands, a tension means at the bottom of said endless 75 bands, on the inside thereof, means for turning said endless bands, said endless bands passing over the rolls and tension means, and means for raising and lowering the rolls and their supporting means, in order to apply greater or less tension to the endless 80 bands enabling the face of said endless bands to be alined.

2. In a device of the character described, a series of rolls and means for supporting 85 same, a tension means, a series of endless rubber bands passing over said rolls and said tension means, a handle, means connected to the supporting means for the rolls and said handle, whereby by the turning of 90 the handle the said tension means are increased or diminished.

3. In a device of the character described, a series of rolls, a shaft, said rolls supported on said shaft, means on said rolls for separately turning the same, a tension means 95 capable of being depressed or relaxed, a series of endless rubber bands, said bands passing over said rolls and over said tension means, a stem, and said stem loosely connected to said shaft, a handle, said handle engaging with the upper part of said stem, whereby by turning the handle the said shaft and rolls and rubber bands are raised or lowered, said tension device increasing 100 or decreasing the amount of tension applied to the said bands.

In testimony whereof, I affix my signature at Cincinnati, Ohio, this 17th day of September, 1921.

WILL T. CRESSLER.
